JAR HOLDER

Hal B. Holland, Praise, Ky., assignor, by direct and mesne assignments, of seven-thirtieths to I. S. Pineur, Pikeville, Ky., seven-thirtieths to Claude Lemons and Stanley Lemons, Cynthia, Ky., and thirty-two one-thousand-one-hundred-twenty-fifths to Zella Powell, Praise, Ky.

Application December 7, 1936, Serial No. 114,701

2 Claims. (Cl. 81—3.3)

This invention relates to jar holders, and its general object is to provide a holder that is primarily designed for use with fruit jars and the like of the type having screw caps and which is capable of being easily and expeditiously clamped upon a jar, for holding the latter rigidly and firmly, without fear of damage or breakage thereto, and to facilitate the application and removal of the cap thereof.

5 A further object of the invention is to provide a jar holder of the character set forth, that can be readily fixed to any suitable supporting means, in position for use, is simple in construction, inexpensive to manufacture and extremely 10 efficient in operation, use and service.

15 This invention also consists in certain other features of construction and in the combination and arrangement of the several parts, to be hereinafter fully described, illustrated in the accompanying drawing and specifically pointed out in the appended claims.

20 In describing the invention in detail, reference will be had to the accompanying drawing wherein like characters denote like or corresponding 25 parts throughout the several views, and in which:

Figure 1 is a top plan view of the jar holder which forms the subject matter of the present invention, and

20 Figure 2 is a front view thereof with parts in section.

Referring to the drawing in detail, the reference numeral 1 indicates a base plate for the holder, which is shown in Figure 1 as being of a particular shape in outline, but in any event 35 the plate is flat and has secured thereto and depending therefrom brackets 2 which threadedly receive screw clamping members 3 of the thumb type, these members having serrated heads 4, for cooperation with the plate in securing the holder in position for use, as will be 40 apparent upon inspection of Figure 2, it being obvious that the holder can be fixed to a table or the like through the instrumentality of the clamping members.

45 Secured to and rising from the base plate is a post 5 that has formed on the opposite sides thereof ears 6 arranged in superimposed pairs with openings therein to receive pins 7 that pass through one of the eyed ends 8 of arcuate band 50 sections 9, for pivotally securing the sections with respect to the post, for cooperative association with each other, as will be apparent upon inspection of Figure 1.

The confronting faces of the band sections 9 55 have secured thereto by rivets or the like 10.

strips 11 of flexible material such as rubber, the strips being substantially co-extensive with the length of the sections and having corrugated faces providing jar gripping teeth 12.

Secured to and rising from the base plate 1 5 is a post 14 that has mounted thereon for rocking movement a connecting member 15 which is held accordingly by a cotter pin as shown, and the connecting member is provided with a reduced inner end having an ear 16 formed thereon, while the outer end portion is relatively thick 10 and terminates in spaced ears 17 between which is pivotally mounted a lever 18 having a handle 19 formed on the outer free end thereof.

The opposite ends of the sections 9 have eyes 15 formed thereon for receiving pins 20 which act to pivotally secure the arms of substantially U-shaped links 21 thereto, as best shown in Figure 2, from which it will be noted that the eyes which are indicated by the reference numeral 22 20 are in the form of sectional hinge barrels and have the arms of the U-shaped links disposed between the same. Each of the U-shaped links 21 are provided with ears which for distinction are indicated by the reference numerals 23 and 25 24, and the ears 23 and 16 have mounted therein the arms of a substantially U-shaped connecting link 25 which is removable therefrom, as will be apparent upon inspection of Figure 2, so that similar shaped links of various lengths 30 are interchangeable to vary the diameter of the jar clamping ring formed by the sections 9, so that the holder can be used with jars of various sizes.

The ear 24 has pivotally secured thereto one 35 end of a band link 26, while the opposite end is pivotally secured to an ear 27 that is formed on the enlarged portion of the connecting member 15, as best shown in Figure 1, and the band link 26 is guided in its movement by a roller 40 30 which is mounted on a post 28 secured to and rising from the plate 1.

An arcuate rack bar 29 is fixed to the plate 1 adjacent to the forward edge thereof, and is arranged so that its teeth are disposed in the 45 path of the lever 18, for holding the lever against movement as will be apparent.

In the use of my jar holder, it is believed that it will be obvious that the lever 18 is disposed toward the right in the form as shown, to open 50 the clamping sections or jaws, and when fully opened, a jar is placed between the same. Movement of the lever toward the left will bring the jaws together for disposing the gripping teeth 12 in engagement with the jar, and as the jaws 55

- are held accordingly, by the application of the lever in the teeth of the rack bar 29, it will be apparent that the hands of the user are free for the application or removal of the cap of the jar.
- 5 Due to the fact that the lever is pivotally mounted with respect to the connecting member 15, it can be readily moved into and out of the teeth of the bar 29 in disposing the jaws with respect to the jar.
- 10 It is thought from the foregoing description that the advantages and novel features of the invention will be readily apparent.

It is to be understood that changes may be made in the construction and in the combination 15 and arrangement of the several parts, provided that such changes fall within the scope of the appended claims.

What I claim is:

1. A jar holder comprising a base plate, co-
20 operating jar receiving arcuate shaped clamping jaws, toothed gripping means secured to the confronting faces of the jaws, anchoring means fixed to the plate and having one of the ends of the jaws pivoted thereto, a post secured to and rising
25 from the plate, a connecting member rockably mounted on the post, a U-shaped link detachably connecting the opposite end of one jaw to one end of the connecting member, a flexible link connecting the opposite end of the other jaw ad-
30 jacent to the opposite end of the connecting member, roller guiding means for the flexible

link, a handle pivotally secured to the connecting member for adjusting the jaws with respect to each other, rack means secured to the plate for receiving the handle to hold the jaws in adjusted positions, and means for detachably securing the holder in position for use and mounted on the plate.

2. A jar holder comprising a base plate, co-
operating jar receiving jaws, toothed cushion means secured to the confronting faces of the jaws, anchoring means fixed to the plate and having one of the ends of the jaws pivoted thereto, hinge barrels formed on the opposite ends of the jaws, means secured to the plate for rocking movement, links pivoted in the hinge barrels, ears formed on the links and the rocking means respectively, a U-shaped link detachably mounted in the ear of one of the first mentioned links, and one ear of the rocking means, a flexible link having its ends connected to the ear of the other link of those first mentioned, and the other ear of the rocking means, and cooperating with the U-shaped link for pivotally connecting the jaws to the rocking means, roller guiding means for the flexible link, a handle secured to the rocking means for moving the latter to adjust the jaws toward and away from each other, and rack means secured to the plate for receiving the handle to hold the jaws in adjusted positions.

30 HAL B. HOLLAND.
